UNITED STATES PATENT OFFICE.

WILLIAM J. NOBLE, OF NEW YORK, N. Y.

DESIGN FOR A BURIAL-CASKET.

SPECIFICATION forming part of Design No. 13,703, dated March 6, 1883.

Application filed December 20, 1882. Term of patent 14 years.

To all whom it may concern:

Be it known that I, WILLIAM JAMES NOBLE, of the city, county, and State of New York, have invented and produced a new and original Design for Burial-Caskets, of which the following is a full, clear, and exact description.

Reference is to be had to the accompanying drawings, forming part of this specification, in which similar letters of reference indicate corresponding parts in all the figures.

Figure 1 is a perspective view of my newly-designed burial-casket. Fig. 2 is a side elevation of a part of the same enlarged. Fig. 3 is a plan view of a part of the same enlarged, these three views being deemed necessary to fully illustrate my design.

The leading feature of my design consists in the ornamental corners of the casket.

A represents the body, and B the top of the casket. The sides and ends of the body A are surrounded by ornamental moldings C, giving them the appearance of being paneled. The corners of the body A, between the top frame, J, and the bottom H, are concaved, and in the recesses thus formed are placed columns D, provided at top and bottom with ornamental carvings. The corners of the bottom H of the casket project beyond the columns D as a base to the said columns, and are rounded, as shown in Figs. 1 and 2. The corners of the style I and the frame J of the top are rounded, and project beyond the columns D as a cap to the said columns, as shown in Figs. 1, 2, and 3. Upon the top of the corners of the top frame, J, directly above the columns D, are placed cylindrical blocks E, the sides of which are provided with ornamental carvings. The cen-

tral part of the tops of the blocks E is flat, or nearly so, and their side parts are beveled, and are provided with angular recesses F. The 40 edge of the top B is beveled, and in the bevels are formed angular recesses G. The inner parts or angles of the angular recesses F G are deepest, and their outer parts are in line with the edges of the bevels in which the said recesses are formed.

I claim—

1. The design for a burial-casket, consisting of the cylindrical blocks upon the corners at the top of the casket, substantially as shown 50 and described.

2. The design for a casket herein shown and described, the same consisting of the ornamental cylindrical blocks upon the corners of the casket directly above the corner columns, 55 and having the side parts of their tops beveled and provided with angular recesses.

3. The design for a burial-casket, consisting of the top having a beveled edge provided with angular recesses therein, and the cylindrical 60 blocks at the corners of the top, substantially as shown and described.

4. The design for a burial-casket, consisting of the recessed corners having ornamental columns therein, the blocks at the top of the 65 casket above the corner columns, and the top having a beveled edge provided with angular recesses therein, substantially as shown and described.

WILLIAM J. NOBLE.
